UNITED STATES PATENT OFFICE.

JAMES DUNN SWANCY, SR., OF AUGUSTA, GEORGIA.

RAILROAD-CROSSING SIGNAL.

Application filed December 27, 1924. Serial No. 758,367.

To all whom it may concern:

Be it known that I, JAMES DUNN SWANCY, Sr., a citizen of the United States, residing at Augusta, in the county of Richmond and State of Georgia, have invented certain new and useful Improvements in Railroad-Crossing Signals, of which the following is a specification.

This invention relates to a device commonly known in the art as a railway crossing signal, the same being adapted to be operated by the wheels of a passing train, to operate a signalling device, disposed adjacent the highway, at the point crossed by the tracks to notify occupants of the highway of pending danger.

The principal object is to generally improve upon devices of this class, by providing one which embodies novel train controlled means associated with the tracks at a desirable distance from the highway, and being operable upon a signalling device, including a visible semaphore structure, and an audible signalling device, in the form of a mechanically operated bell.

The foregoing structural details are associated in a novel structural arrangement, the advantages of which will be apparent from the following description, considered in connection with the accompanying drawing:

In the accompanying drawing, forming a part of this application, and in which like numerals are employed to designate like parts throughout the same:

Figure 1 is a side elevation of a fragment of a railroad track, showing the train control means and signalling device, adapted to be disposed adjacent the highway.

Figure 2 is a top plan view of Figure 1, with portions of the train control means shown in section, to disclose the structure more clearly.

Figure 3 is a detail view of the upper portion of the signalling device.

Referring to the drawings, it will be seen that the train control means comprises an elongated rectangular casing or housing 1, positioned between the rails of the track. At the opposite ends of this housing and located within the same are appropriate bearings 2, in which a shaft 3 is journaled for rotation. The opposite ends of the shaft extend beyond the end walls of the casing and are equipped with pointed tappets 4. These tappets are disposed at the

inner sides of the rails, and the pointed upper ends thereof extend a slight distance above the surface of the wall of the rails, so that they will be actuated by the periphery of the train wheels passing thereover. I would direct attention to the fact that the intermediate portion of the rotary shaft is somewhat thickened as at 5, and small coil springs are connected thereto on opposite sides. This arrangement counterbalances the shaft, and facilitates operation and resetting. With this arrangement, it will be seen that I have provided a rather sensitive structure which will operate readily and efficiently, and wherein the major parts are enclosed in the housing, to protect them from dust, dirt, and the elements.

As before indicated, the signalling device is disposed alongside one of the tracks and adjacent to the crossing highway, as indicated in Figure 2. Although the signalling device might be constructed otherwise, it preferably comprises a vertical standard 7, securely anchored in the ground, and provided at its top with a Y-shaped head 8. Mounted on the arms of this head are duplicate semaphore arms 9. They are preferably mounted intermediate their ends and the inner opposed ends are connected with small links 10, which are in turn connected with a pull rod 11. The pull rod extends upwardly, and is connected at its top, through a short link 12, to a crank arm 13 extending outwardly from a rotary shaft 14. This shaft is journaled in bearings at the upper ends of the arms of a U-shaped frame 15, also carried by the standard. A bell 16 is hung from the central portion of the shaft and is sounded simultaneously with the operation of the semaphore arm. In order that the bell may swing freely, the upper portions of the arms of the U-shaped frame are offset slightly as seen more plainly in Figure 3. For the purpose of operating the semaphore arms and bell, a steel wire cable 17 is employed. This is connected at one end to the central portion of the aforesaid shaft 3, in a position to have a pull exerted upon it, when the said shaft is rocked. The cable extends between the rails, as shown better in Figure 2, and is trained around a pulley 18, extending at right angles therefrom at 19, passing over pulleys 20 at the base of the standard, and then upwardly, as at 21, the same being con-

nected at its upper end to the aforesaid pull rod 11. Assuming now that the train, travelling in the direction of the arrow, Figure 1, passes over the tappet 4, the same will be depressed by the peripheral portions of the wheels and the shafts 3 will be rocked against the spring tension. A pull will thus be exerted upon the cable, and inasmuch as the latter is connected to the semaphore arms and bell, through the medium of the mechanism and linkage described, it is obvious that the semaphore arms 9 will be raised to a horizontal display position, while at the same time the mechanically operated bell will be sounded. A dual signal will thus be given to warn the occupants of the highway of an approaching train. Although I have not shown it, it is within my idea to equip the semaphore arm signalling light to render the device more useful at night.

It is thought that the foregoing description, taken in connection with the drawings, will enable persons to obtain a clear understanding of the same. Therefore, a more lengthy description is thought unnecessary.

Although I have shown and described the preferred embodiment of the invention, it is to be understood that minor changes coming within the field of invention claimed may be resorted to, if desired.

I claim:

1. A railroad crossing signalling device comprising a standard, a head at the upper end of said standard, semaphore arms pivotally mounted upon said head, links connected to the inner ends of said arms, a vertically disposed pull rod connected with the inner ends of said links, a frame also supported on the upper end of said standard, a shaft journaled for rotation in said frame, a mechanically operated bell carried by said shaft, a crank arm on the shaft, said pull rod being connected with said crank arm, and a train controlled cable for operating said arms and bell.

2. In a structure of the class described, train controlled means comprising a casing adapted for transverse disposition between the rails of the track, a shaft journaled for rotation in said casing, the outer ends of the shafts extending beyond the outer ends of the casing, tappets carried by said extended ends adapted to be operated by the peripheral portions of the train wheels, the intermediate portion of said track being counterbalanced, and said counterbalancing means comprising springs for returning the shaft to a normal set position.

In testimony whereof I affix my signature.

JAMES DUNN SWANCY, Sr.
